UNITED STATES PATENT OFFICE.

LUTHER L. KNOX, OF BELLEVUE, PENNSYLVANIA, ASSIGNOR TO BLAW-KNOX COMPANY, OF PITTSBURGH, PENNSYLVANIA, A CORPORATION OF NEW JERSEY,

PORT-COOLER FOR REVERSING REGENERATIVE FURNACES.

1,385,008.

Specification of Letters Patent. Patented July 19, 1921.

Application filed March 27, 1918. Serial No. 225,123.

To all whom it may concern:

Be it known that I, LUTHER L. KNOX, a resident of Bellevue, in the county of Allegheny and State of Pennsylvania, have invented a new and useful Improvement in Port-Coolers for Reversing Regenerative Furnaces, of which the following is a full, clear, and exact description, reference being had to the accompanying drawings, forming 10 part of this specification, in which—

Figure 1 is a vertical section of one end portion of an open hearth furnace embodying my invention;

Fig. 2 is a section on the line II—II of Fig. 1;

Fig. 3 is a view partly in front elevation and partly in vertical section of the port cooler removed;

Figs. 4 and 5 are, respectively, plan and 20 end views of the same;

Figs. 6 and 7 are sections taken, respectively, on the lines VI—VI and VII—VII of Fig. 3;

Fig. 8 is a view similar to Fig. 6, and 25 showing a modification; and

Figs. 9 and 10 are detail sectional views of the dome.

My invention has relation to port coolers for reversing regenerative furnaces, and 30 more particularly to the long type of coolers which extend transversely substantially the full width of the furnace, as shown in my Patent No. 1,070,486 of August 19, 1913, and my Patent No. 1,085,139 of January 27, 35 1914, upon which the present invention is an improvement.

The object of the present invention is to improve the construction of the cooler, whereby it is stiffened or strengthened with 40 respect to crushing and buckling stresses while rendered more flexible under stresses due to expansion and contraction.

A further object is to provide a port cooler of this type having an improved construction which will permit of a lower floor for the air ports without materially decreasing the thickness thereof. A still further object is to provide the cooler with means for insuring an effective water circulation 50 and the elimination of all steam which may be formed therein.

Referring to the accompanying drawings, in which I have shown the preferred embodiment of my invention and which will 55 now be described, the port cooler as shown

therein is, in general, of the long form described and claimed in my said patents, extending substantially the full width of the furnace. It consists of a sheet metal, box-like structure having the sloping forward wall 2, the downwardly and forwardly sloping top wall 3, the central portion 4 having the arched port opening 5 therethrough, and the laterally extending end portions 6. The structure may be conveniently made from 60 sheet metal, and the joints are preferably formed by welding in any suitable manner, the use of rivets being preferably avoided where possible. The port opening 5 slopes in a downward and forward direction, and 70 has an arched top wall 7, the central portion 4 of the structure above the arch 7 being also arched and of higher elevation than the top lines of the end portions 6, the curve of this arch portion merging into the top wall 75 of the portion 6. In this manner, the end portions of the structure are reduced in height, thereby enabling the floor of the air port 8 of the furnace to be made lower than would otherwise be necessary, without sacrificing the thickness of such floor. At the same time, a sufficient body of the cooling 80 fluid is provided above the arched wall of the port opening 5.

The side, top, bottom and end walls of the 85 structure are preferably formed with corrugations 9, pressed therein. These corrugations materially stiffen the structure against crushing, collapsing and buckling stresses, while at the same time they render the walls 90 thereof sufficiently flexible to compensate for expansion and contraction stresses. This is of importance in a welded structure, since these corrugations materially assist in protecting any tendency of the welds to open 95 under expansion and contraction stresses.

I also preferably provide the front central portion of the structure with a corrugation 10, extending around the port opening 5. The side walls of said opening are also preferably corrugated, as indicated at 11, and the floor of such opening is also shown as having corrugations 12. The structure may further be stiffened by the interior corner bracings 13, which can be welded in place 105 during the formation of the structure and before the ends thereof are closed.

If desired, the structure may be provided with an internal system of bracing, such as shown in Fig. 8, in which the side, top and 110

bottom walls of the structure are provided with lugs or projections 14, to which are connected preferably somewhat loosely jointed bracing members 15, thus providing an effective interior bracing having the necessary element of flexibility.

It will be readily seen that the interior of the structure forms a receptacle capable of containing a considerable volume of water which is continuous throughout and which entirely surrounds the port opening 5. When the structure is in place in the furnace, this port opening 5 registers with the gas port 16 of the furnace in the manner clearly shown in Fig. 1. The upper portion of the structure is embedded in the floor 17, between the gas and air ports, while the lower portion of the structure seats within the floor of the gas port 16. Preferably the lower central portion of the structure has the forwardly projecting flange 18, which forms a seat for a filling 19 of refractory material. The entire port opening 5 is lined with refractory material, as indicated at 20, and the corrugations formed in the walls of this opening assist in retaining such lining in position. The forward upper central portion of the structure is preferably provided with the depending hollow arched lip 21.

Water may be introduced into the interior of the structure in any suitable manner. For this purpose, I have shown the structure as having a pipe 22, extending longitudinally throughout its lower portion. This pipe is preferably provided with a coupling 23, at each end, and in use a supply pipe may be coupled to either end as may be most convenient, the other end being plugged. The pipe 22 is provided with two discharge branches 24, which deliver the water at the lower central portion of the structure at each side of the arch.

The arched central top portion of the structure is formed with a dome 25, shown in detail in Figs. 9 and 10, this dome being provided with a T connection 26, with an outlet pipe 27 for the hot water and steam, this pipe extending the full width of the structure and being arched upwardly at the central portion to conform to the arched form of such portion. Preferably this pipe will be arranged to discharge at both ends, although it may be plugged up at one end, if desired.

The vertical arm of the T 26 extends upwardly within the dome in the manner best shown in Fig. 9, and is screwed into a ring 28, which is carried by a series of lugs 29, welded to the inside of the cap portion 30 of the dome. This cap portion is formed separately and after being screwed on the T until stopped by the lug extensions 29, is welded to the body portion of the dome,

as indicated at a in Fig. 9. This insures a proper support for the pipe 27, and also insures a clear passageway above the upper end of the T for the escape of hot water and steam. This dome, as will readily appear from Figs. 3 and 4, is located at the central rear part of the arched central portion of the cooler structure and at the highest part thereof, so that the hot water, together with all steam, will readily flow into the dome and thence out of the pipe 27. This effectually prevents the formation of pockets of steam within the interior of the structure.

The entire structure can be readily put in place and removed and renewed when necessary, as in the case of my previous patents above referred to.

I do not wish to limit myself to the particular construction and arrangement of parts which I have herein shown and described, since obviously these may be widely varied within the scope of the appended claims. For instance, the particular shape of the cooler may be changed and any suitable system of interior bracing may be employed, the corrugations may be differently arranged, and various other changes may be made.

I claim:

1. A port cooler for the gas ports of reversing regenerative furnaces having a raised central portion, a hollow dome in said central portion closed at its top and communicating with the interior thereof, and an outlet pipe lying longitudinally within the structure and having an arm extending upwardly within the dome, there being a free steam and water passage within the dome to the open end of said arm, said pipe, arm and dome forming means whereby the hot water and steam rising into the dome are carried to the ends of the structure, substantially as described.

2. A port cooler for the gas ports of reversing regenerative furnaces having a raised central portion provided with a hollow dome closed at its top and communicating with the water space of the interior of the structure, an outlet pipe lying longitudinally within the structure and having an arm extending upwardly within said dome, said pipe, arm and dome forming means whereby the hot water and steam rising into the dome are carried to the ends of the structure, and a support for said arm within the dome, substantially as described.

3. A port cooler for the gas ports of reversing regenerative furnaces, comprising a hollow sheet metal box-like structure having an arched port opening extending therethrough, a water inlet pipe extending longitudinally of the structure below the said opening and having discharge branches at

opposite sides of said opening, the central portion of the structure above said opening having a closed top dome, and an outlet connection for hot water and steam extending within said dome, said end portions constituting the major portion of the total length of the structure and being of a depth to extend at least as low as the floor level of said port, whereby the said opening is completely inclosed at its sides, substantially as described.

In testimony whereof, I have hereunto set my hand.

LUTHER L. KNOX.
